UNITED STATES PATENT OFFICE

2,156,627

MATERIAL FEEDING MECHANISM

Clifford E. Harrison, Philadelphia, Pa., assignor to American Engineering Company, Philadelphia, Pa., a corporation of Pennsylvania

Original application January 16, 1935, Serial No. 2,034, now Patent 2,100,741, dated November 30, 1937. Divided and this application September 22, 1937, Serial No. 165,042

5 Claims. (Cl. 198—226)

This application is a division of my co-pending application Ser. No. 2,034, filed January 16, 1935, for Material feeding mechanisms, now Patent 2,100,741, granted November 30, 1937, and the invention herein involved relates to ram cylinders of the type employed in material feeding devices.

Rams and the cylinders therefor which are constructed in the usual manner with smooth continuous contacting surfaces, have been found, under certain conditions, when employed for feeding purposes, to bind to such an extent that serious damage occurs to the operating parts. This binding action usually occurs after the device has been in operation for a considerable period of time and has become worn so that a substantial clearance exists between the rams and cylinders. Due to this clearance, siftings are more readily drawn between the ram and cylinder when the former recedes after a feeding operation. The ram also tilts slightly about a transverse axis during its movement in the cylinder. Because of this tilting action these materials have a tendency to accumulate more rapidly near the outer end of the cylinder and upon successive operation of the ram these materials become packed to such an extent as to form a non-compressible scale in the form of a wedge, tapering downwardly toward the inner end of the cylinder. Upon successive operations of the ram additional materials are drawn into the cylinder and finally the mass becomes so packed that the ram cannot be withdrawn after a feeding stroke, and as a result serious damage occurs to the operating parts.

One object of the present invention is to provide an improved ram cylinder construction which will eliminate the above mentioned difficulties.

A more specific object is to provide in a ram cylinder of the stated character longitudinally extending grooves, or other irregularities in the inner surface thereof, whereby a broken surface is presented to the associated ram which prevents binding of the latter due to siftings.

Other and further objects will become apparent as the description of the invention progresses.

Of the drawing:

Fig. 1 is a side elevational view partly in section of a ram and cylinder assembly employing the present invention.

Fig. 2 is a plan view partly in section, of a ram cylinder showing spiral grooves provided in a portion of the inner surface thereof.

Fig. 3 is a plan view partly in section of a

modification of the structure shown in Fig. 2, and

Fig. 4 is a plan view of a still further modification of the structure shown in Fig. 2.

Referring to the drawing, the numeral 1 indicates generally one form of ram and ram cylinder to which the present invention may be applied. This general construction is shown and described in United States Patent No. 1,958,639, granted to Herbert E. Preston, and assigned to the American Engineering Company, to which reference may be had for a full disclosure thereof.

Ram 2 comprises a fuel feeding portion 4, which in the present instance is secured to a base 5 by any suitable means, such as by bolts 15 6, and is operated by a crank shaft 7 through a connecting rod 8 extending through the outer or right hand end of the ram and pivoted to the base portion 5 thereof, as shown at 9. Thus, upon rotation of crank 7, ram 2 will be reciprocated in the cylinder 3. Cylinder 3 is provided with a liner element 11' constructed of wear resisting material. The portion of the ram box beneath the hopper 12 is also provided with wear plates 13. Cylinder 3 also has provided 25 near the right hand end thereof a band of packing 14 held in place by a metallic ring 16, and a second ring 17 extends between the packing 14 and the end of the cylinder. These elements are held in place in any suitable manner, such 30 as by bolts 18, as shown in Fig. 1.

Referring to Fig. 2, it is seen that the liner element 11' of cylinder 3 is provided with a series of approximately longitudinally disposed, spiral grooves 26. The side walls of these grooves 35 diverge slightly from right to left (Fig. 2) to facilitate the removal of the siftings accumulating therein. By this construction it is seen that the grooves 26 provided in the liner element 11' present a broken surface to the siftings drawn between the ram and its cylinder, and thus packing of the siftings into a hard scaly mass, which eventually causes binding of the ram, is prevented.

In Fig. 3 the liner element 11'' is shown provided with a series of longitudinally disposed grooves 27. The side walls of these grooves also diverge slightly from right to left of the cylinder. In this construction the grooves are straight 40 rather than spiral, as shown in Fig. 2.

In Fig. 4 the liner element 11''' is shown provided with a series of projections 28 instead of the spiral or straight grooves 26 and 27 shown in Figs. 4 and 5 respectively. By this construction the contacting surface is broken up into a 45 50 55

series of spaced points, and packing of the siftings trapped between the ram and the cylinder is reduced to a minimum.

It is understood that when no liners are employed the grooves 26, 27, or the projections 28 shown in Figs. 2, 3 and 4, may be provided in the cylinder wall proper.

From the foregoing description, it is seen that because a broken surface is presented to the siftings trapped between the ram and its cylinder the action of the ram on such siftings is momentary rather than continuous, and as a result the siftings cannot be compressed into a non-compressible scaly mass which finally causes binding of the ram and damage to the associated parts. These constructions are especially desirable in connection with stoker furnaces wherein continuity of service is of great importance. By eliminating binding of the rams in such devices the life of the operating parts is not only prolonged, but efficient operation is maintained without danger of binding of the parts or damage to the operating elements.

While the embodiments herein described are admirably adapted to fulfill the objects primarily stated, it is to be understood that the invention is not to be limited thereto since it may be embodied in other forms, all coming within the scope of the claims which follow.

What is claimed is:

1. A ram cylinder of the class described, having an annular ram engaging surface provided with longitudinally disposed indentations, said indentations forming a series of irregularities in the said ram engaging surface whereby contact with the ram adapted to operate in said cylinder is made only at spaced points. 5

2. A ram cylinder having an annular ram engaging surface provided with a series of grooves extending longitudinally thereof in spaced relation, and the side walls of said grooves diverging toward the inner end of said cylinder. 10

3. A ram cylinder having an annular ram engaging surface provided with a series of spiral grooves extending approximately longitudinally thereof. 15

4. A ram cylinder having an annular ram engaging surface, provided with a series of spiral grooves extending approximately longitudinally thereof, and the side walls of said grooves diverging toward the inner end of said cylinder. 20

5. A ram cylinder of the class described, having an annular ram engaging surface provided with a series of grooves extending longitudinally thereof, and the said ram engaging surface having an annular groove provided near one end thereof adapted to receive packing material. 25
